POURING OR DROPPING VESSEL

Sophie Scheyer (née von Pezachowicz) and
Sandro Arcari, Munich, GermanyApplication July 24, 1937, Serial No. 155,382
In Germany June 3, 1936

9 Claims. (Cl. 221—148)

The invention relates to pouring or dropping vessels, the pouring devices of which are provided with so-called capillary grooves. Such vessels with capillary grooves in the pouring device are 5 known per se.

The object of the invention is vessels such as bottles or the like having a capillary groove provided on the spout opening, the base of which, in longitudinal section, is curved in an essentially syphon-like manner from the inside to the outside, for controlling the out-flowing stream of liquid, e. g. for measuring drops out of the bottle or for preventing the final drop after the termination of flow from the bottle.

15 One of the aims of the invention is to provide dropping bottles which completely satisfy for the measuring of the drops which is necessary in practice and are, however, cheap and capable of being manufactured by mass production by a simple pressing process. Such dropping-bottles, particularly as used by chemists for preparing medicines, must give drops for example so accurately and uniformly that there are always twenty drops to each gramme of water. The control 20 of this dropping of the bottle is an object of the present invention.

According to the invention it is proposed that the capillary groove, widening in known manner preferably towards the mouth, is narrowest and deepest at the highest portion thereof, i. e. at the upper edge of the bottle. The groove at its highest part is preferably less than one mm. broad, preferably $\frac{1}{16}$ to $\frac{1}{8}$ mm., whereas its depth at this place is more than 1 mm.

30 35 The groove has preferably transverse grooves which according to the invention are situated in the outwardly and downwardly directed portion of the capillary groove and are preferably sharp edged.

40 Further features of the invention will appear from the description in which several examples are described with reference to the accompanying drawing which are substantially to scale.

45 Fig. 1 shows a bottle with a capillary groove, according to the invention.

Fig. 2 shows another embodiment of the bottle according to the invention in which two transverse grooves are provided on each side of the capillary groove.

50 Fig. 3 shows a bottle, the capillary groove of which has quite a series of short transverse grooves on each side.

Fig. 4 is a top plan view of Fig. 1.

55 Fig. 5 shows a section through the neck of the

bottle in the longitudinal direction of the capillary groove.

Bottles 1 are shown in the drawing, which have spout-like projections 2 in which capillary grooves 3 are provided in known manner.

As can be seen from Fig. 5, the bottom 4 of the capillary groove 3 is curved in a syphon-like manner from the inside to the outside. The groove is very narrow at its highest portion at 5 (Fig. 4) and broadens towards the interior of 10 the bottle as well as outwardly towards the mouth end of the groove.

Practical tests with bottles according to the invention constructed for trial, have shown that to obtain the above stated conditions, i. e. about 15 20 drops of water to the gramme, the breadth of the groove at its highest part at 5, should be less than 1 mm. and preferably $\frac{1}{16}$ to $\frac{1}{8}$ mm., whereas the depth of the groove at this point should be somewhat more than 1 mm. The flattened 20 mouth-end of the groove will not be made much broader than 2 mm.

As can be seen from Fig. 4, the groove also broadens from the highest point at 5 towards the inside. The mouth of the bottle is indented 25 at 6 in the direction of the highest portion of the groove in order that the largest possible amount of water may accumulate above the narrowest portion of the groove during the dropping of the liquid. For the same purpose the 30 groove, shortly before the highest part thereof at 5, and towards the inside at 9, will be deepest.

When the bottle is inclined during dropping, the liquid, at first, collects in the deepened and broadened part of the groove before the narrowest part 5, since the liquid cannot immediately pass through the narrow part of the groove. The liquid then sucks itself through the narrowest part of the groove at 5 without any further inclination of the bottle and then reaches 40 the broadened part of the groove which flattens towards the mouth end thereof. Once the liquid has reached the mouth end dropping begins without any substantial further inclination of the bottle. By means of this arrangement it is possible to make the dropping from the bottle substantially independent of trembling of the hand or of slight shaking of the bottle. The size of the drops is essentially dependent upon the breadth of the capillary groove at its highest 50 point. The broadening of the groove towards the mouth end which is known per se, has in this case particular significance during dropping in as much as the liquid must only pass through a very small space at the narrowest portion of the 55

capillary groove, so that it can thereafter flow substantially freely and after the liquid emerges from the narrowest portion of the groove the formation of the drops can be effected by other means.

5 A number of other features of the grooves affect the uniformity and the size of the drops. The flattening of the groove towards the mouth end causes the drops to be smaller because by this 10 means the volume and capacity of the groove are decreased.

15 For influencing the size of the drops a shorter projection 7 (Figs. 1 and 2) is also of importance. The projection 7 has approximately the breadth of the mouth end of the bottom of the groove. The projection serves to effect the retaining and falling of the drops. The inclination of the projection to the axis of the bottle as well as its length in the direction of the bottom of the 20 groove determine the size of the drops and the frequency of dropping. A sharply pointed projection will increase the frequency. On the other hand, with larger projections, the drops forming at the mouth end remain attached longer and 25 thereby gain time to increase in size. A shortening of the projection will therefore cause a reduction in the size of the drops.

30 Transverse grooves 8 extending from the main groove in a sideways direction have proved to be essential for influencing the size of the drops and the frequency of dropping. The arrangement of transverse grooves is already known in capillary grooves in order to prevent dripping after the termination of pouring from a container provided with such a groove. However, 35 in the present invention the transverse grooves have another significance in as much as they are intended to influence the frequency of dropping. They may therefore act as a kind of brake. The 40 uniformity of the single drops and therewith the size of the drops can also be influenced by the transverse grooves.

45 In Figs. 2 and 3 dropping bottles are shown in which the downwardly and outwardly directed part of the capillary grooves have transverse grooves. The transverse grooves 8 shown in Fig. 2 cut relatively deeply into the material of the side walls. The bottom of the side grooves is situated at substantially the same height as the bottom of the main groove. Dropping tests with 50 distilled water from bottles the groove of which has the dimensions specified above and possesses two transverse grooves on each side of the main groove have shown that 21 drops can be obtained from one gramme of water.

55 The transverse grooves 8 shown in Fig. 3 are substantially shorter than the grooves shown in Fig. 2. The transverse grooves 8 of Fig. 3 are also formed with sharp corners. In this embodiment five short transverse grooves are provided 60 on each side of the main groove.

65 The influencing of the speed of flow during dropping is achieved in that the flowing liquid is subjected only to a fluid friction at the fluid filled transverse grooves 8, whereas, in the absence of the transverse grooves, it is subjected to the entire wall friction. By the suitable choice of the number and depth of the transverse grooves in the downwardly directed part of the 70 main groove, the dropping liquid as well as the uniformity of the drops can easily be controlled. The transverse grooves 8 have furthermore the importance that they form spare quantities of liquid, which during a too small flow from the 75 bottle, e. g. if the hand is not held sufficiently

steady during pouring nevertheless maintain the drops uniform. On the other hand, it can be achieved that, by the provision of transverse grooves, even during too great a flow through the groove, the superfluous amount of liquid, e. g. 5 during the first drops, will be received in the transverse grooves 8. The transverse grooves 8 on the dropping groove 3 thus operate something like the known sluices or the space between the sluices in the regulation of river flow. 10

15 In the grooves formed according to the invention, which are very narrow in their highest part, the provision of auxiliary grooves overlying the main groove has been shown to be very advantageous when they are such as to lie over 20 the small main groove so that the wall of the groove descends step-wise to the base thereof. The dropping of certain liquids demands very narrowly formed grooves of a few tenths of a millimetre. In such cases, it is occasionally difficult to send the liquid through the narrow part of the groove in order to wet it, in order that the dropping may be reliable from the start. If, however, a wider groove is laid over the narrower one, one can easily send the first drops of liquid 25 through the broader overlying groove and after the lower narrower groove has been wetted by the first drops, only allow the liquid feed for the further drops to pass through the narrow groove. Even in such cases, transverse grooves could be 30 provided. The depths of the transverse grooves could conveniently be so chosen that the transverse grooves extended to the wall of the over-laid auxiliary groove.

35 Practical tests with glass bottles according to 40 the invention have shown that by employing the described features, the number of drops from one gramme, e. g. of water, can easily be controlled from 10 to 30. The present invention is naturally not limited to glass bottles but is applicable to liquid containers of porcelain, earthenware, German silver, aluminum, enamel, silver and other metals.

45 In the manufacture of such grooves in porcelain vessels definite rules must be observed if it is desired to stop dripping after the end of flow with reliability. For example, in capillary grooves, the base of which runs from the inside to the outside in substantially syphon form in the shape of a semi-circle, in longitudinal section, the apex of the spout must be exactly in the middle. The grooves should widen out in the forward end of the spout, in a funnel shape in the direction of flow and they should be somewhat elongated and pointed in the backward 55 direction towards the inside of the spout. Besides, the interior of the vessel and the grooves must be free from all unevenness and steps which might prevent return flow of the liquid and act as a dam. Furthermore, the grooves should be 60 rightangled in cross-section and have sharp corners. The extreme end of the spout should also be sharp cornered.

65 In order to prevent subsequent changes in the shape of the groove during the firing, one preferably so proceeds in the case of porcelain vessels, that after molding the vessel is slowly dried and fired in order to avoid distortion. Before glazing the fired bodies the groove is, according to the invention, wetted with a brush and if necessary remodelled in order to regain the desired 70 form which may have been damaged by the firing. After the immersion of the vessel in the glaze and the subsequent firing thereof, the glazing on the groove can be easily removed since, 75

as a result of the previous wetting, it does not adhere to the porcelain. Then, with the help of a brush a thin glaze is put on the walls of the groove and firing takes place again for a short time. In this manner the sharp cornered property of the groove which increases adhesion, and the semicircular form thereof are retained, and not distorted by the usual glazing. This process can be repeated several times for thick glazes.

10 We claim:—

1. In a dropping vessel, a spout, a capillary groove of non uniform depth and width in the spout the bottom of said groove curved like a syphon, and side walls of said groove shaped as to define the narrowest and deepest cross-section of said capillary groove in the region of the highest point of its syphon-curved bottom.

2. In a dropping vessel, a spout, a capillary groove of non uniform depth and width in the spout the bottom of said groove curved like a syphon, and side walls of said groove shaped as to define the narrowest and deepest cross section of said capillary groove in the region of the highest point of its syphon-curved bottom, and 25 to diverge towards the outer and inner ends of the capillary groove.

3. In a dropping vessel, a spout, a capillary groove of non uniform depth and width in the spout the bottom of said groove curved like a syphon, side walls of said groove shaped as to define the narrowest and deepest cross section of said capillary groove in the region of the highest point of its syphon-curved bottom, and a downwardly directed lip at the outer end of the groove.

35 4. In a dropping vessel, a spout, a capillary groove of non uniform depth and width in the spout the bottom of said groove curved like a syphon, and side walls of said groove shaped as to define the narrowest and deepest cross section of said capillary groove in the region of the highest point of its syphon-curved bottom, the side walls defining transverse grooves, extending outwardly from their inner surfaces, between said cross section and the outer end of the capillary groove.

45 5. In a dropping vessel, a spout, a capillary groove of non uniform depth and width in the spout the bottom of said groove curved like a

syphon, and side walls of said groove shaped as to define the narrowest and deepest cross section of said capillary groove in the region of the highest point of its syphon-curved bottom, the side walls defining sharp edged transverse 5 grooves extending outwardly between said cross section and the outer end of the capillary groove.

6. In a dropping vessel, a spout, a capillary groove of non uniform depth and width in the spout the bottom of said groove curved like a 10 syphon, and side walls of said groove shaped as to define the narrowest and deepest cross section of said capillary groove in the region of the highest point of its syphon-curved bottom, the width of said cross section not exceeding and its 15 depth exceeding one millimeter.

7. In a dropping vessel, a spout, a capillary groove of non uniform depth and width in the spout the bottom of said groove curved like a syphon, and side walls of said groove shaped as 20 to define the narrowest and deepest cross section of said capillary groove in the region of the highest point of its syphon-curved bottom, said groove being longer outwardly from said cross section than inwardly.

25 8. In a dropping vessel, a spout, a capillary groove of non uniform depth and width in the spout the bottom of said groove curved like a syphon, and side walls of said groove shaped as to define the narrowest and deepest cross section 30 of said capillary groove in the region of the highest point of its syphon-curved bottom, said bottom being substantially straight outwardly from said cross section and longer there than inwardly.

35 9. In a dropping vessel, a spout, a capillary groove of non uniform depth and width in the spout the bottom of said groove curved like a syphon, and side walls of said groove shaped as to define the narrowest and deepest cross section 40 of said capillary groove in the region of the highest point of its syphon-curved bottom, said bottom being but slightly curved outwardly from said cross section and longer there than inwardly.
